SHOE ROUGHING MACHINE

Charles G. Brostrom, Peabody, Mass., assignor to
 United Shoe Machinery Corporation, Paterson,
 N. J., a corporation of New Jersey

Application September 20, 1934, Serial No. 744,823

7 Claims. (Cl. 69—1)

This invention relates to shoe roughing machines and is particularly concerned with the provision of improved mechanism for facilitating the presentation of the overlasted margin of a shoe upper to a roughing tool of such a machine.

In roughing the margin of the upper of a lasted shoe the shoe is held in the hands of an operator and must be presented accurately and with the right amount of pressure to the tool, to secure a uniformly roughed surface without damaging the thin upper leather.

It is an object of the invention to provide an improved mechanical work rest or guard with the aid of which the operator can easily and accurately control the presentation of the work to the tool and can produce perfect results, even though he may not be particularly skilled.

With this object in view the invention provides a bowl-shaped work rest or shield within which a portion of a rotary roughing tool is received and against the upper edge or rim of which the bottom of the insole of a lasted shoe is adapted to be pressed and tilted to subject the overlasted margin of the upper to the action of the rotating tool.

The bowl-shaped rest is preferably freely rotatable, permitting the shoe to be moved past the roughing tool with a minimum of effort while the exposed portion of the periphery of the tool acts across the rim of the bowl toward the axis thereof.

In the illustrated form of the invention there is also embodied an improved work rest mounting in which provision is made for adjustment of the bowl in an arc concentric with the axis of the roughing tool to facilitate presentation of a shoe to the tool in a position best suited to the individual operator; other adjustments permit the bowl to be kept close to the operating part of the tool, regardless of changes in the size of the tool resulting from wear and resharpening.

The foregoing and other features and advantages of the invention will be better understood and appreciated from reading the following detailed description of one practical embodiment thereof in connection with the accompanying drawing, in which

Fig. 1 is a perspective view of a practical form of the invention; and

Fig. 2 is a view, partly in elevation and partly in vertical section, showing the internal structure of the work rest and its mounting.

In the drawing, 10 indicates a rotating shaft upon which is mounted a roughing tool 12 of any desired type, but preferably one of those shown and described in my copending application Serial

No. 594,529, filed Feb. 23, 1932, and which has become Letters Patent of the United States No. 1,989,078, granted January 29, 1935.

14 indicates a stationary portion of the frame of the machine which is provided with an arcuate T-slot 16, concentric with the axis of the shaft 10 of the rotating roughing tool 12. In the arcuate guide slot 16 is mounted a support 18 which may be adjusted in said slot in a path concentric with the axis of the roughing tool and secured in any desired position therein by a wing nut 20.

The support 18 is bored to receive a horizontally adjustable arm 22 which is prevented from rotating by a spline 24 and has a threaded end 15 portion, as shown at 26, to receive an adjusting nut 28. An expansion spring 30 holds the nut 28 against the support 18, to maintain the adjustment.

The forward end of the arm 22 carries a hub 20 32 having a vertical bore through which passes a vertically adjustable carrier 34 for a bowl-shaped work rest or guard 36. The bowl carrier 34 is prevented from rotation in the hub 32 by a spline 38 and has its lower end portion threaded 25 as shown at 40 to receive an adjusting nut 42 which is held against the under side of the hub 32 by an expansion spring 44.

The upper end of the bowl carrier 34 carries a ball-bearing 46 upon which the bowl 36 is 30 adapted to rotate freely about an upright axis. The bowl-shaped work rest or shield 36 has a thin edge or rim, which may be corrugated as shown at 48 to prevent slipping of the work thereon, adapted to engage the bottom of the insole 50 of a 35 lasted shoe 52 which may be pressed against said rim to facilitate accurate presentation of the overlasted margin 54 of the shoe upper to the action of the roughing tool 12.

By adjustment of the work rest support 18 40 along the arcuate slot 16 the front portion of the rim of the bowl 36 may be moved up or down about the periphery of the roughing tool without otherwise altering the relation between the tool and the work rest. Thus the apparatus may be 45 adjusted to facilitate presentation of the shoe to the roughing tool at the angle best suited to the operator, having regard to ease of handling the shoe and watching the operation of the roughing tool thereon.

Having described the invention, what is claimed as new and desired to be secured by Letters Patent of the United States is:

1. In a shoe roughing machine, the combination of a bowl-shaped rotary work rest and a 55

- rotary roughing tool positioned partly within said rotary work rest, the axes of rotation of the work rest and the roughing tool being substantially at right angles to each other.
5. 2. In a shoe roughing machine, the combination of a bowl-shaped, free, rotary guard, and a rotary roughing tool positioned partly within said rotary guard, the exposed portion of the periphery of the tool being rotatable toward the rim of the bowl.
10. 3. In a shoe roughing machine, the combination of a bowl-shaped freely rotatable work rest, and a rotary roughing tool having its periphery acting across the rim of the bowl toward the axis thereof.
15. 4. In an upper roughing machine, a bowl-shaped shield having a thin upper edge adapted to be brought into contact with the bottom of the insole of a lasted shoe to serve as a rest about which the shoe may be tilted, and a roughing tool rotating within said shield for roughing the overlasted margin of the shoe upper.
20. 5. In an upper roughing machine, a hollow bowl-shaped guard mounted for rotation about an upright axis with the forward portion of its

upper edge exposed for the application of work thereto so that the upper edge of the guard may be caused to roll along the bottom of the insole of a lasted shoe presented to the machine, and means for roughing the overlasted margin of the 5 shoe upper above the edge of the guard.

6. In a shoe roughing machine, a rotating roughing tool, a bowl-shaped work rest in which a portion of said rotating tool is received, the bowl having a thin upper rim engageable by the 10 insole of a lasted shoe while said tool operates on the overlasted margin of the shoe upper, and a work rest mounting upon which said rest can be adjustably moved around the tool in a path 15 concentric with the axis of the latter.

7. In a shoe roughing machine, a bowl-shaped work rest freely rotatable about an upright axis, a rotating roughing tool partly received in the bowl, a vertically adjustable bowl carrier, a horizontally adjustable arm sustaining the carrier and a support for the arm, which support is adjustable in an arc concentric with the axis of rotation of the tool.
